TUBE STILL

Ralph M. Parsons, Mount Vernon, Ohio, assignor to The Ralph M. Parsons Company, Mount Vernon, Ohio, a corporation of Delaware

Application March 2, 1935, Serial No. 8,988

2 Claims. (Cl. 196—110)

This invention relates to furnaces and more particularly to tube stills for the treatment of hydrocarbon oils.

An object of the invention is to provide a furnace for the above purpose which is cheap and simple in construction, efficient in operation and adaptable to various uses in oil refining and cracking plants.

Another object is to provide a furnace in which the tubes are arranged to absorb heat efficiently, to protect and shield the furnace walls and to transfer heat to the liquid within the tubes at the maximum permissible rate.

Another object is to provide a furnace which may be altered by simple changes in connections to accommodate different types or grades of oil.

Another object is to provide a furnace that is adapted to operate as a cracking furnace or a combination cracking and reforming furnace or for other purposes which may arise in an oil refining plant.

Various other objects and advantages will be apparent as the nature of the invention is more fully disclosed.

Although the novel features which are believed to be characteristic of this invention will be pointed out more particularly in the claims appended hereto, the invention itself, as to its objects and advantages and the manner of its application, will be better understood by referring to the embodiments thereof disclosed in the accompanying drawing and more specifically described herein for purposes of illustration only.

In the drawing:

Fig. 1 is a vertical transverse section through a furnace constructed in accordance with this invention, showing the tubes in a conventional manner; and

Fig. 2 is a similar view showing a different embodiment of the invention.

In the various figures, like parts have been designated by like reference characters.

Specific terms are used herein for convenience of description but it is to be understood that they are to be interpreted as broadly as the state of the art will permit.

Referring to the drawing more in detail, the invention is shown in Fig. 1 as applied to a furnace having a floor 9, side walls 10 and 10' and a center wall 11 separating the lower part of the furnace into a pair of combustion chambers 12 and 13. The walls 10, 10' and 11 are preferably arranged so that the combustion chambers 12 and 13 are rectangular in shape and are comparatively narrow.

The walls 10, 10' may be supported in any convenient manner, as by stays 14, and may be carried upon a suitable foundation 15 through which air ducts 16 and fuel pipes 17 may extend. Each air duct 16 terminates at a burner 20 or 20' which may, for example, comprise a block of refractory material having a flared passage 21 formed therein, similar in shape to a Venturi tube. The fuel pipe 17 terminates in a jet 22 which is so disposed with respect to the passage 21 that the flow of fuel gas through said passage induces the required flow of air for combustion purposes through the duct 16. The flared passage 21, in addition to assisting the maintenance of the required flow of fuel gas and air, also provides an efficient mixing device for thoroughly mixing the air with the fuel whereby complete combustion may be obtained without the addition of secondary air.

The burner 20 may be formed of a block of high grade refractory material but in order to reduce the cost thereof it is preferable to form the burner of a cheaper grade refractory and to line the passage 21 at the exit side thereof with a lining 23 of a material adapted to withstand intense heat, such for example as a high chrome refractory.

The burners may extend through the floor 9 of the furnace and are adapted to direct the flame upwardly in the combustion chambers 12 and 13. The burners are preferably of sufficient length so that combustion begins within the burner and has reached a point at the exit of the burner such that a substantial amount of heat is available for the lower tubes within the combustion chambers. It is to be understood that a row of such burners extends longitudinally of each combustion chamber so as to apply heat uniformly along the tubes, to be described. The air ducts 16 may be omitted provided other means is provided to obtain the proper air supply for the burners. Obviously the burners may be of any other desired type, the above being given as an example only.

The furnace is also provided with a convection chamber 30 located above the combustion chambers 12 and 13 and having a cross section substantially less than that of said combustion chambers. The convection chamber 30 is formed by side walls 31 which are joined to the side walls 10, 10' by roof sections 32. The walls 31 and 32 thereof may be supported in any convenient manner (not shown) as for example from a framework 33 of structural shapes which may be located externally of the furnace walls. A hood 55

34 is mounted over the walls 31 of the convection chamber 30 and may be supported by structural members 35, carried by the stays 14. The hood is adapted to direct gases from the convection chamber 30 to a stack 36. Disposed within the convection chamber 30 is a bank of convection tubes 40 connected for the passage of the fluid being treated, for example oil, from the upper to the lower tubes of said bank. The side wall 10 and the center wall 11 of the combustion chamber 12 may be lined with sets of wall tubes 41 and 42 respectively, which extend longitudinally of the furnace and are sufficiently close to the path of the flame to extract heat therefrom both by radiation and convection. The lower tubes may be mounted at a level corresponding to the zone at which combustion has progressed sufficiently to raise the flame to the required temperature for efficient heating. The wall tubes 41 and 42 are closely spaced so as to substantially shield the walls of the combustion chamber 12 from the intense radiant heat of the flame. It is accordingly possible to construct the walls of a low grade refractory material or of an insulating material. The walls may have a coating 10a of insulating material on the outside so as to form a more effective seal. In certain cases it may be desirable to cast or form the walls monolithic in which case the insulating coating may be omitted as the walls themselves would then be gas tight.

Sets of side wall tubes 43 and center wall tubes 44 are located in the combustion chamber 13 in a position to shield the walls 10' and 11 of said chamber and to receive heat by radiation and convection in a manner similar to tubes 41 and 42 above described. The tubes 43 and 44 may be arranged in one or more layers as, for example, in two layers as illustrated in Fig. 1, so as to obtain the desired rate of heat transfer as for example, a rate suitable for "soaking" or maintaining the oil at a given temperature. A set of side wall tubes 45 may be mounted adjacent the side wall 10' above the tubes 43 so as to completely shield the upper part of said side wall from the flame.

It is to be understood that the various tubes above described may be supported in any convenient manner, as for example from the stays 50 or structural members 35, the manner of support forming no part of the present invention.

The tubes above mentioned may be connected in various sequences, depending upon the use to which the furnace is to be applied and the nature 55 of the fluid to be treated. In the example illustrated in Fig. 1, the fluid is supplied to the bank 40 of convection tubes from a line 46, is passed downwardly through the convection tubes countercurrent to the path of the combustion gases. 60 It is thence supplied by a line 47 to the side wall tubes 41, is passed downwardly through said tubes, thence through a line 48 to the center wall tubes 42, thence outwardly through a line 49. Fluid may also be supplied through a line 65 50 to the side wall tubes 45 and may pass downwardly through said side wall tubes, thence through the side wall tubes 43, thence through a line 61 to the center wall tubes 44, thence outwardly through a line 62. Provision is made by 70 means of a pipe 53, controlled by a valve 54, to interconnect the lines 49 and 50 so as to permit the fluid to pass directly from the center wall tubes 42 to the side wall tubes 45, and suitable means, such as valves 55 and 55', may be

provided to close the external connections to the lines 49 and 50.

In the above described furnace, the side and center wall tubes are located sufficiently close to the path of flame so that they receive a substantial amount of heat by radiation and also are traversed by the combustion gases and absorb heat by convection therefrom. The flame is thus reduced in temperature before it reaches the tubes in the convection chamber 30 to a point such that injury to the lower tubes in said chamber is prevented. The combustion gases, however, still contain a substantial amount of heat which is removed by the convection tubes 40 before the gases reach the stack 36.

It is to be noted that the path of the gases from the burners 20 to the stack 36 is substantially vertical and without appreciable change in direction. By this construction the resistance to the flow of gases is reduced to a minimum and the necessity for a high, expensive stack is avoided.

The use of two combustion chambers 12 and 13 permits independent adjustment whereby the rate of heating of the fluid may be controlled. For example, when used in an oil cracking plant preheating may occur in the convection chamber 30, the oil may be further heated to cracking temperature in the wall tubes 41 and 42 of the combustion chamber 12 and may be maintained at that temperature for a substantial period of time in the wall tubes 43, 44 and 45 associated with the combustion chamber 13. In such case the combustion chamber 13 constitutes a soaking zone in which the oil is maintained at cracking temperature a predetermined length of time.

It is obvious that various changes may be made in the direction of oil flow, the numbers of tubes in each set, the velocity in the different chambers and in the adjustment of the burners so as to heat the oil in its passage through the furnace at predetermined rates adapted to obtain any desired temperature gradients.

In some instances the combustion chambers 12 and 13 may be used for different purposes. For example, the valve 54 may be closed and the valves 55 opened to make external connections to the lines 49 and 50 so that oil for cracking may be supplied through line 46, passed through the convection tubes 40 and through the wall tubes 41 and 42 of the combustion chamber 12 and out through line 49. Other oil, for example oil to be reformed, may be supplied to the furnace through the line 50 and passed through the tubes 43, 44 and 45 in the combustion chamber 13 and thence outwardly through the line 52, the rate of combustion being adjusted to provide proper temperature control in each chamber.

In the case of a small plant it may be desirable to operate the furnace at times as a cracking unit and at other times as a combination cracking and reforming unit. In such event, the above construction reduces the furnace cost and avoids the necessity for maintaining two furnaces.

In certain plants, the type of oil varies from time to time. The invention provides means for adapting the furnace to use with such various types of oil by separately controlling the rate of combustion in the two combustion chambers in accordance with the requirements in each particular case.

Since the convection chamber is of smaller cross-section than the combustion chamber, the velocity of gases over the tubes 40 is greater than

the velocity over the wall tubes. The proportion can be made such, taking into consideration the available heat and the desired rate of transfer, that the convection tubes and wall tubes operate with maximum efficiency to extract heat from the combustion gases and the heating effect is distributed as desired between the various sets of tubes. In general, the increased velocity compensates for the lower heat content of the gases in the convection chamber and increases the heat transfer to the convection tubes.

A simplified form of furnace is shown in Fig. 2 in which a single combustion chamber 59 is used in place of the two combustion chambers 12 and 13 of Fig. 1. The furnace in Fig. 2 comprises a floor 60 and a pair of side walls 61 forming the combustion chamber 59. Side walls 62, joined to the side walls 61 by roof sections 63, form a convection chamber 64. A supporting framework 65, hood 66 and stack 67 may be arranged in the manner set forth in connection with Fig. 1. A row of burners 68, similar to the burners 20 above described, may be located in or near the floor 60 to direct the flame upwardly toward the stack 67. A bank of convection tubes 69 is located in the convection chamber 64 and the walls 61 may be lined by side wall tubes 70. The wall tubes 70 may extend to a point opposite the tip of the burners 68 for the purpose to be described.

In the operation of this furnace, a fluid such as oil may be supplied through a line 71, may pass downwardly through the convection tubes 69, thence through side wall tubes 70, and out through a line 72. The side wall tubes 70 are located closely adjacent the path of the flame so as to receive heat by radiation and convection therefrom and to substantially reduce the temperature of the flame before the gases reach the convection tubes 69.

The burner 68 is sufficiently long so that combustion begins therein and heats a portion of the burner to radiance. The lower side wall tubes consequently receive heat by radiation from the burner and the tubes thereabove receive heat by radiation from the flame as it emerges from the burner and by convection from the combustion gases. The entire space within the combustion chamber is accordingly utilized efficiently for the transfer of heat from the fuel to the fluid within the tubes.

This type of furnace is particularly adapted to oil cracking plants inasmuch as the oil is first heated in the convection tubes 69 and is thereafter quickly raised to cracking temperature in the side wall tubes 70. The arrangement may be such that certain of the tubes constitute a soaking section and maintain the oil at required temperatures. Obviously, the side wall tubes may be used in more than one layer if desired, as illustrated in connection with the tubes 43 and 44 of Fig. 1.

Although a specific type of furnace has been disclosed for purposes of illustration, it is obvious that various changes and modifications may be made therein by a person skilled in the art without departing from the scope of the present invention. The invention is only to be limited in accordance with the following claims when interpreted in view of the prior art.

What is claimed is:

1. A two cell upshot oil cracking still comprising, in combination, side walls forming a rectangular furnace chamber, a central vertical longitudinal wall in the lower part of said furnace chamber dividing said chamber into a pair of narrow vertical combustion chambers communicating at their upper parts above said center wall, additional side walls located above said first walls and offset inwardly therefrom to form a convection chamber narrower than said furnace chamber located directly above and spaced from said center wall to receive gases equally from both combustion chambers, a hood above said convection chamber to receive combustion gases therefrom, a bank of horizontal convection tubes carrying hydrocarbon oil substantially filling said convection chamber, vertical rows of horizontal side wall radiant heat tubes adjacent said first side walls to shield the same from radiant heat and additional vertical rows of horizontal tubes on both sides of said center wall to shield the same from radiant heat, said additional rows terminating at the top of said center wall whereby an unobstructed passage is provided from said combustion chambers to said convection chamber, and a row of burners spaced longitudinally along the bottom of each combustion chamber to direct a flame upwardly between said rows of side wall tubes toward said convection tubes.

2. A two cell upshot oil cracking still comprising, in combination, side walls forming a rectangular furnace chamber, a central vertical longitudinal wall in the lower part of said furnace chamber dividing said chamber into a pair of narrow vertical combustion chambers communicating at their upper parts above said center wall, additional side walls located above said first walls and offset inwardly therefrom to form a convection chamber narrower than said furnace chamber located directly above and spaced from said center wall to receive gases equally from both combustion chambers, a hood above said convection chamber to receive combustion gases therefrom, supporting means for said side walls and hood comprising a framework located entirely outside of said walls, said framework having vertical members adjacent to and supporting said first walls, other vertical members supported thereby and located adjacent to and supporting said additional side walls and members supported by said first vertical members and supporting said hood, a bank of horizontal convection tubes carrying hydrocarbon oil substantially filling said convection chamber, vertical rows of horizontal side wall radiant heat tubes adjacent said first side walls to shield the same from radiant heat and additional vertical rows of horizontal tubes on both sides of said center wall to shield the same from radiant heat, said additional rows terminating at the top of said center wall whereby an unobstructed passage is provided from said combustion chambers to said convection chamber, and a row of burners spaced longitudinally along the bottom of each combustion chamber to direct a flame upwardly between said rows of side wall tubes toward said convection tubes.

RALPH M. PARSONS.
